UNITED STATES PATENT OFFICE.

ROBERT CHARLES MONTEAGLE, OF NEW YORK, N. Y., ASSIGNOR OF ONE-HALF TO E. MANN VYNNE, OF NEW YORK, N. Y.

HEAT-CONDUCTING TUBE.

SPECIFICATION forming part of Letters Patent No. 770,599, dated September 20, 1904.

Application filed April 6, 1903. Serial No. 151,236. (No model.)

To all whom it may concern:

Be it known that I, ROBERT CHARLES MONTEAGLE, a citizen of the United States, and a resident of Morris Heights, in the city of New York, county and State of New York, have invented certain new and useful Improvements in Heat-Conducting Tubes, of which the following is a specification.

My invention relates to an improvement in tubes intended for use in such devices as evaporators, condensers, or similar purposes where it is desired to conduct heat between fluids which are respectively within and without the tube.

15 The object of my invention is to produce a tube for such purposes which shall have a greater conductive capacity than an ordinary plain tube and which is also less liable to become loosened by the variations in temperature to which it may be subjected.

A further object of my invention is to produce a tube of the character described which may be cheaply and readily manufactured by processes which are commercially practicable.

25 Other objects of my invention will appear from an inspection of the description and claims hereunto appended.

In the drawings, Figure 1 represents an exterior view of a tube, a portion of one end 30 of the same being in section; and, Fig. 2 is a cross-section of the tube.

Corresponding parts in all the figures are denoted by the same reference characters.

The body A of my improved tube consists 35 of a series of longitudinal bulged or convex convolutions B, which are substantially radial in cross-section and which are coiled or pass helically about the axis of the tube and are separated from each other by helically-extending 40 grooves or depressions concave in cross-section and of a width approximately equal to the width of the bulged or convex convolutions. This effect is produced by first rolling or otherwise forming the tube so as to produce the radial convolutions and then twisting the tube thus formed. The cross-section shown in Fig. 2 gives the appearance 45 of the tube before twisting. When the tube is twisted, the convolutions approach nearer

to each other than is shown in Fig. 2. A short section C at the ends of the tubes is left cylindrical in shape to facilitate adjustment of the tubes to the heads of boilers or condensers. The peculiar shape of these tubes thus formed produces a whirling action 55 of the liquid in passing through the same, which insures intimate contact of the liquid with the surfaces of such character that the conduction of heat through the walls of the tube is much increased. A tube of this character also possesses marked advantages in other ways. The body of the tube possesses a flexibility much greater than any straight tube would possess, and therefore can give both by bending and extension or compression, 65 so that the strains which variation in temperature tend to produce are compensated for in the body of the tube. This relieves the point of attachment of the tube in the head from the strains which with ordinary tubes tend to 70 loosen the joint and cause leaks. This form of tube is thus specially well adapted for use in condensers, as it has a high conducting power and may be kept tight in the heads.

The material of the tube may be anything 75 which it is possible to work into the shape desired. Copper or a ductile material resembling copper is a desirable and preferable material to use in a majority of cases.

It will be noted that in the improved construction of the tube comprised in my invention the central bore or main passage is of relatively reduced diameter or area, and a series of distinct chambers are formed to extend outwardly and project from said central 85 bore or passage and helically surround the same, said outer chambers being constituted by a series of helical convolutions surrounding the central passage, which is of relatively narrow or reduced diameter. The helical 90 convolutions form the chambers opening into the central passage and a series of deep depressions intermediately of the chambers and projecting inwardly to the central passage, 95 which intermediate helical depressions preferably correspond approximately in their depth and width to the chambers. In the preferred construction the mouths or open-

ings of the distinct chambers into the central passage are of reduced width with relation to the body of the chamber.

The improved construction and arrangement, as above noted, is such that the greater interior area of the tube is in the outer chambers and not in the central bore or passage, whereby the passage of steam or other media through the tube is sufficiently retarded to enhance efficiency in operation, and the improved construction also provides in a given compass a maximum area of effective and active operative surface.

I do not desire to be understood as limiting myself to the details of construction and arrangement as herein described and illustrated, as it is manifest that variations and modifications may be made in the features of construction and arrangement in the adaptation of the device to various conditions of use without departing from the spirit and scope of my invention and improvements. I therefore reserve the right to all such variation and modification as properly fall within the scope of my invention and the terms of the following claims.

Having thus described my invention, I claim and desire to secure by Letters Patent—

1. A heat-conducting tube of the class described having a central bore or main passage of relatively reduced diameter or area and a series of distinct chambers extending outwardly and projecting from said central bore or passage and helically surrounding the same, said outer chambers being constituted by a

series of helical convolutions surrounding the central passage, the chambers opening into the central passage and a series of deep depressions intermediate of the chambers and projecting inwardly to the central passage, the construction and arrangement being such that the greater interior area of the tube is in the outer chambers and not in the central bore or passage.

2. A heat-conducting tube of the class described having a central bore or main passage of relatively reduced diameter or area and a series of distinct chambers extending outwardly and projecting from said central bore or passage and helically surrounding the same, said outer chambers being constituted by a series of helical convolutions surrounding the central passage, the chambers opening into the central passage and a series of deep depressions intermediate of the chambers and projecting inwardly to the central passage, the mouths or openings of said chambers into the central passage being of reduced width with relation to the body of the chamber and the construction and arrangement being such that the greater interior area of the tube is in the outer chambers and not in this central bore or passage.

In testimony whereof I have signed my name in the presence of the subscribing witnesses. 65

ROBERT CHARLES MONTEAGLE.
